(57) **CLAIM**

The ornamental design for a protector and shock absorber for a pillar of a storage structure, as shown and described.

DESCRIPTION

FIG. 1 is a perspective view from the front, top, and left side of the protector and shock absorber for a pillar of a storage structure;

FIG. 2 is a perspective view from the front, below and left side thereof;

FIG. 3 is a perspective view from the rear, below and the right side thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof, the right side elevational view being a mirror image thereof; and,

FIG. 9 is a perspective view showing the protector and shock absorber for a pillar of a storage structure in place of a pillar which is shown in dotted lines.

The broken lines in FIGS. 2, 3 and 7 are by way of illustration only and form no part of the claimed design and the broken lines defining the pillar in FIG. 9 illustrate environment only and form no part of the claimed designs.
